UNITED STATES PATENT OFFICE

2,571,958

COOLING TOWER

Gibbs M. Slaughter and George Puls,
Fort Worth, Tex.

Application September 27, 1948, Serial No. 51,452

1 Claim. (Cl. 261—95)

1

This invention relates to cooling towers, and has reference to a construction for cooling liquids, such as water, used in industrial power plants, air conditioning buildings, and the like.

An object of the invention is to provide a proportionately smaller tower than those used heretofore for cooling a given volume of liquid from a known temperature to a required lower temperature.

Another object of the invention is to eliminate louvers heretofore used near the bases of cooling towers, and thereby reduce the height of the feed line, and thus effect a reduction in the cost of pumping the liquid to the top of the tower.

A further object of the invention resides in the provision of a distributing bucket arrangement whereby little, if any, liquid is blown from the top of the tower.

These and other objects of the invention will become apparent from the following description of the accompanying drawings, wherein:

Figure 1 is an elevational and sectional view of a cooling tower embodying the features of the present invention.

Figure 2 is a perspective view of a tubular tile employed in the packing of the form of the invention illustrated in Figure 1.

Figure 3 is a broken elevational view of a modified form of packing.

Figure 4 is a view similar to Figure 3, and illustrating a further modified form of packing.

Figure 5 is a partial plan view of the upper portion of the cooling tower illustrated in Figure 1.

Figures 6, 7 and 8 are lateral sectional views taken on lines 6—6, 7—7 and 8—8, respectively, in Figure 1.

Figure 9 is an enlarged sectional and elevational view of the packing supporting means, and

Figure 10 is a broken lateral sectional view of the side of a square aerating tube and showing corrugations therein for increasing the aerating surface.

The cooling tower illustrated in Figure 1 includes a rectangular concrete basin 1 having a square case 2 supported thereon by means of transverse lintels 3 extending across the upper edges of the basin walls. By reason of the described construction, air is permitted to enter the basin 1 at the upper extending ends thereof, as indicated by the arrows in Figure 1. An overflow pipe 4 is provided in one wall of the basin 1 to determine the liquid level in the lat-

2

ter, whereas a suction line 5 is similarly provided in one wall of the basin 1 and near the bottom of the same for returning the cooled liquid to its source. The case 2 is preferably made of masonry, but within the scope of the invention other materials may be substituted. Near the upper end of the case 2 there is a deck 6 having an opening 7 in its center. The periphery of the opening 7 is upturned, as at 8, where it supports a vertical cowling 9 around a horizontal and centrally disposed fan 10. A radial support 11 is positioned within the opening 7 in the deck 6 and has a reduction gear 12 positioned at its center and on which the fan 10 is mounted. A motor 13 is mounted on the deck 6 and is connected with the reduction gear 12 by means of a shaft 14 extending through the cowling 9. The case 2 may be extended upwardly above the deck, and a stair 15 may be provided outside said case for convenience in reaching and maintaining the upper portion of the structure.

Inverted T-beams 16 are positioned across the upper edges of the basin 1 and parallel with the lintels 3. The flanges of the T-beams engage and support opposing lower edges of straight cells 17, such as ordinary rectangular hollow tile used for the walls of buildings. It will be noted that the last referred to cells 17 are tubes within the meaning of the present invention.

The packing 18 in the preferred form of the invention, Figure 1, consists of multiple tubes 19 of ceramic or other material having cross partitions 20 extending therethrough. The ends of the tubes 19 are obliquely formed relative to the lengths thereof, and which ends are parallel with each other. A lower layer of tubes 19 are stacked in rows with corresponding ends upon the straight cells 17 and cover the plane defined by the latter. Subsequent layers of tubes 19 are stacked one upon the other in staggered relation relative to the layer of tubes therebeneath in the manner illustrated in Figure 1. Within the scope and spirit of the present invention straight cells 17 may be stacked one upon the other in spaced staggered relation to form the packing 18, as illustrated in Figure 3. Similarly, and as shown in Figure 4, the packing 18 may be in the form of cylindrical tubes 21 having ends formed at right angles with respect to their axial centers, and which tubes are also stacked in staggered relation with respect to the layers of said tubes.

Above the uppermost layer of tubes 19 at the top of the packing 18, and shown in Figure 1,

there are stacked pyramids of inverted channel members 22 which support distribution or overflow buckets 23. The last referred to channel members 22 are inverted for distributing overflow liquid evenly over the described pyramid arrangements.

Beneath the deck 6, as illustrated in Figures 1 and 7, there is a feed line 24 which supplies the liquid to be cooled to distributing pipes 25. The distributing pipes 25 are positioned over the buckets 23 and liquid therefrom is conducted downwardly into said buckets by means of nozzles 26 connected with said distributing pipes.

The corrugated or raked surface 27 of the tubes, particularly illustrated in Figure 10, has to do with increasing the area of the liquid film over the tubes 17, 19 or 21, and may be applied to the members 22 of the described pyramids. However, it is to be understood that such corrugated surface is referred to by way of example and not as a limitation. It is also to be understood the ceramic material referred to, which tends to cooling the liquid, is also recited by way of example and not as a limitation.

In operation, the liquid to be cooled is delivered to the buckets 23 through the feed line 24, the distributing lines 25, and the nozzles 26. The water overflows the perimeters of the buckets 23, from where it descends by gravity over the supporting channels 22, and downwardly through 30 the packing 18. By reason of the described staggered relation of the tubes 17, 19 or 21, the liquid being aerated is distributed to all of said tubes and thinly disbursed over and through the same. After passing through the supporting straight cells or tubes 17, the aerated water falls into the basin 1 from where it is returned to its source, either through the overflow 4 or the suction line 5.

As the liquid moves downwardly from the buckets 23 to the basin 1, an induced draft is effected by the fan 10 within the cowling 9. The direction of the draft is downwardly through the extending ends of the basin 1, upwardly through the packing 18 and over the pyramided

supporting channels 22, thence outwardly through the cowling 9. The induced draft further aerates and cools the liquid. The shape and arrangement of the supporting channels 22 allow passage of air therethrough and trap a portion of the liquid from the overflow buckets 23 therein. Accordingly, very little, if any, liquid is blown outwardly of the cowling 9 by the fan 10.

The described form of the invention is not restrictive, but may be made in many ways within the scope of the appended claim.

What is claimed is:

A cooling tower comprising, in combination, a rectangular basin, a case supported on said basin inwardly of the ends thereof, a deck covering the upper end of said case, an annular upturned cowling around an opening in the center of said deck, a driven fan mounted in said opening and arranged to draw air upwardly therethrough, inverted T-beams arranged in spaced parallel relation across the lower end of said case, cells having vertical openings therethrough supported on the flanges of said T-beams, other cells stacked on the first said cells, downwardly directed water outlets in the upper end of said case and beneath said deck, upright distribution overflow buckets beneath said outlets and supported on the top of said cells.
